UNITED STATES PATENT OFFICE.

THEOPHILUS VAN KANNEL, OF YARDVILLE, NEW JERSEY, ASSIGNOR TO THE
UNIVERSAL BALANCE DOOR INCORPORATED, OF NEW YORK, N. Y., A CORPO-
RATION OF NEW YORK.

WIND AND GRAVITY BALANCED DOOR.

1,272,732.

Specification of Letters Patent. Patented July 16, 1918.

Application filed May 22, 1917. Serial No. 170,236.

To all whom it may concern:

Be it known that I, THEOPHILUS VAN KANNEL, a citizen of the United States, residing at Yardville, county of Mercer, and 5 State of New Jersey, have invented certain new and useful Improvements in Wind and Gravity Balanced Doors, fully described and represented in the following specification and the accompanying drawings, forming

10 ing a part of the same.

This invention relates to a door formed of two wings arranged to swing normally in opposite directions, and provided with suitable connections and means for restoring 15 them to their closed position when anyone passes through the doorway.

The invention is applicable to doors which are exposed to wind-pressure, or are, as in the rolling or pitching of a vessel, subjected to lurching which develops gravity 20 strains. Also to doors affected by inertia, as those upon railway cars.

From either of these causes, an unbalanced door may severely resist the movement of a 25 passenger through the doorway, but oppositely moving door-wings mechanically connected, fully balance such wind-pressure and other strains because the pressures upon the wings are wholly balanced and neutralized.

30 As the wind or rocking of a water-craft tends to close one of the wings and at the same time to open the other, the wings will remain normally at any point whether open or closed, or in any intermediate position, 35 because connected together, and therefore they are readily opened or closed.

The present invention provides an improved form of connections for the door-wings for hinging the doors in different 40 relations to the door-frame, and also means for checking the movement of the doors when they are being closed or opened.

To hold the doors normally closed, it is necessary to provide a spring or weight to 45 automatically close the wings and overcome the friction of the hinges or pivots, and other working parts. It further becomes necessary to provide a proper checking device to make the closing of the wings slow 50 and uniform, in order that they may not move so rapidly in closing as to strike or shove persons passing, and that they may close upon one another without slamming.

It is obvious that a great strain is placed

upon doors generally where their closing 55 movement is caused and controlled by springs and checks. For this reason, I have, in the present invention, devised a series of double connections between the door-wings, such connections consisting of double acting levers 60 and connecting-rods the arrangement being such that while one connecting-rod is pulling, the other has a pushing action.

The checking device is similarly organized, there being two cylinders with their 65 pistons working in liquid opposite each other, so that great strain upon the checking device is entirely balanced and neutralized.

The cylinders and their pistons operate 70 within a control-box, which is also provided with means to stop the closing movement of the doors when they are wholly opened.

These features of construction obviate the 75 use of heavy parts to resist the normal strains, and in connection with the wind and gravity balanced device, result in producing doors that can be swung with very slight effort, and for this reason they are not liable to get out of repair.

The entire connecting and controlling 80 mechanism has been designed to be located across the top or bottom of a doorway and wholly inclosed in a housing, which may, if located at the top, be part of the transom 85 bar and attached beneath it.

The housing and mechanism occupy a vertical depth of only two or three inches, and has a width not more than that of the ordinary transom bar. This construction 90 thus locates the mechanism entirely out of sight, which is a very desirable feature and enhances the architectural appearance of the entrance.

In the normal operation of balanced door-wings, one is necessarily opened outward and the other inward at the same time; but there are cases when doors are installed in buildings like factories, assembly halls, &c., where it is necessary that both wings of the 100 door in emergencies should be capable of swinging outward simultaneously to produce a complete and unobstructed exit.

To accomplish this, I apply to that wing which normally opens inward, a detachable 105 coupler in the connection between the two wings, which coupler operates normally to move the wings in opposite directions but

becomes automatically detached so that the doors may both swing in the outward direction if the inward moving wing is pressed with undue force. With this construction, 5 the doors move normally in opposite directions, but are both capable of moving outward in case of a panic.

The invention includes the duplex connection between the wings of the door to 10 diminish the strain upon each, and a duplex construction for the door-check and the detachable coupler between the inward moving door-wing connections as well as other features of construction which will be herein- 15 after pointed out in the claims.

In the annexed drawing, Figure 1 is a 20 plan of the mechanism within its housing, showing the wings closed; Fig. 2 is an elevation of the same for location beneath the transom of the door, the nearer side of the housing being removed and the floor of the housing being in section; Fig. 3 is a plan of the door-check and the wing-cranks with the rocker shown reverse from its position in Fig. 1, with the wings fully open; Fig. 4 is a vertical section, where hatched, at the center of the pivot, at the left-hand of Fig. 1; Fig. 5 shows the under side of the double lever appearing in the top of Fig. 4; Fig. 6 is a cross section, where hatched, at the middle of Fig. 2; Fig. 7 is a side elevation of the door-check the same as shown in Fig. 2, with the transom and the lower part of the housing in section; Fig. 8 is a plan of the 30 same parts with the rocker in dotted lines and the casing for the door-check shown in section at the center line of the cylinders; Fig. 9 is a longitudinal section of one of the check-pistons showing its valve. 35

In Figs. 2 and 3, door-wings A and B are shown provided with pivots C, C', projecting from their upper edges near the inner sides of the door-frame, shown at D in Fig. 1. Arrows α^4 are applied to the door-wings in Fig. 1 to show the direction of their movements when opening. The transom E at the top of the doorway forms the upper part of the housing, closed at the bottom by a floor G and at the sides by hinged doors G' shown in Fig. 6; which permit access to the mechanism.

The upper bearing for each pivot, as shown in Fig. 4, is formed in a hub I with conical seat I' rounded upon its under side, 55 and resting upon a plate J supported by the floor G. The conical portion I' extends from the hub through the said plate to hold it in position, while permitting the bearing to rock slightly upon its supporting-plate J, 60 so as to accommodate the bearing to any varying position of the wing-pivot.

The pivots shown in Figs. 2 and 4 are formed with a foot-plate J' secured upon the top edge of the door-wing by screws J'. 65

The self-adjusting bearing compensates for

any inaccuracy in the setting of the pivot, or any irregular shrinking of the wood-work. In Figs. 1 to 3 and 7, the casing of the control-box F for the door-check and plunger is shown mounted upon the floor G of the housing intermediate to the pivots, and provided with a spindle a, upon the top of which a rocker b is secured and provided with four crank-pins c and c'.

In Figs. 1 and 3, wing-cranks formed of 75 levers having each two opposite arms d are connected by studs z and connecting-rods d' and d'' to the crank-pins c, c' upon the rocker, and the wing-cranks of the two wings are thus connected to move together and under 80 the control of the door-check.

Springs H and H' are attached respectively to the crank-arms d upon the two door-wings and to fixed pins e upon the housing and arranged, as shown in Fig. 1, to 85 hold the door-wings normally in a closed position, indicated by their overlapping edges f in Fig. 1.

Fig. 1 shows the position of the wing-cranks when the wings are closed; and Fig. 90 3 shows the contrary position when the wings are fully open.

The pivots are located and the wing-cranks proportioned to operate wholly within the sides of the door-frame D, the cranks 95 swinging about 90 degrees.

The connecting-rods d' and d'' are subjected respectively to a pulling and pushing strain, as they are connected to the wing-cranks at opposite sides of the pivots and to 100 the rocker at opposite sides of its spindle a.

The organization of the door-check and its operation upon the rocker is shown in Figs. 6, 7 and 8, the spindle a of the rocker being mounted in the removable top f' and 105 bottom f'' of the casing.

Within this casing a check-crank lever with two arms g is actuated by the spindle, and its opposite ends connected by crank-pins o' to links h, which operate pistons j 110 in cylinders i projected outwardly from opposite sides of the casing. The casing and cylinders are filled with oil or other suitable liquid which furnishes the resistance required. The pistons thus move in opposite 115 directions, which force the liquid in both of them in and out of the cylinders when the check-crank g is oscillated.

The crank-pins o' of the check-crank describe each an arc which produces a practically uniform movement of the plungers; and both resist jointly any sudden closing of the door-wings, by forcing the liquid from the cylinder into the casing. Each piston, as shown in Fig. 9, has a passage k 125 extended through it and provided with a check-valve l', which opens when the wings are opened suddenly, but closes when the wings close, by the action of springs H.

The outer ends of the cylinders i are closed 130

and are connected each by a port l' with an equalizing tube m which discharges the liquid in each cylinder into the casing through a passage n having a regulating screw n' .

The two plungers are thus subjected automatically to the same regulated degree of resistance.

The outer movements of the pistons force 10 the liquid in the outer end of each cylinder back into the casing F through the passages m and n . The screw n' may be so adjusted as to give the wings a uniformly slow movement from their open position to a point 15 nearly closed, the speed of which may be adjusted by the screw, at pleasure.

The port l' is so formed as to be wholly covered by the piston at the outermost end of its stroke, when the wings are closed, and 20 the corner of the piston which passes over such port is beveled to cause a gradual closing thereof, to retard the final closing of the wings. This retarding point can be shifted in relation to the wing-cranks by 25 adjusting the position of the rocker with reference to the wing-cranks. This is effected, as shown in Figs. 1 and 2, by forming the body of the connecting-rods d' and d^2 with screw-threads, and screwing them into the 30 screw-heads d^4 of the connecting-rods, which engage the pins c , c' and the pins or studs z upon the wing-cranks.

If it be desired to make the piston j arrive earlier in its closing movement, the 35 screw-heads are turned to shorten the two rods d' and to lengthen the two rods d^2 equally.

This causes the closing of the piston-port earlier without changing the closing point of 40 the two wings with relation to one another. A change in the connecting-rods may also secure the adjusting of the two wings so as to close simultaneously, without shifting the retarding point above described. In Fig. 6, 45 a permanent stop p is formed upon the housing, and the wing A in Fig. 1 is shown as if in contact with such stop, but if the wing B has not yet contacted with the wing A , then the shortening of the rod d^2 , shown 50 in the upper part of Fig. 1, and the lengthening of the rod d' in the lower part of Fig. 1, which connects the rocker with the wing B , serve to bring the door B in contact with the wing A and without changing the position 55 of the pistons.

It will be noticed that the pins c , c' upon the rocker are placed near one another in pairs to receive the two rods from the corresponding ends of the wing-cranks, the arrangement being such that the arcs described by these pins may be the same as the relative arc on the two wing-cranks.

As best shown in Fig. 8, in addition to the door-check which retards the closing 65 movement of the door, the control-box F is

provided with a plunger to gradually arrest the wings as they reach their full opening.

The plunger q is mounted movably in a cylinder or socket r in line with a toe g' upon one of the check-arms g when the 70 wings are opened. The toe g' is shown by dotted lines in its position at the extreme end of the opening movement, with the face of the plunger expressed by dotted line within the mouth of the cylinder. 75

The spring s holds the plunger normally out to the mouth of the cylinder against a stop s' .

A hole r' is formed through the side of the cylinder adjacent to the inner end of the plunger when in its inward position, to permit the slow escape of oil when the plunger is pressed into the cylinder by the toe g' , the side of the plunger having a bevel e^2 , which first passes over the hole so as to close it 85 gradually, and thus bring the wings to a full stop by arresting the escape of the oil. The oil thus affords a resistance to the wings at the close of their opening movement, the hole e^2 being open when the plunger moves 90 inward.

The spring is inserted in the cylinder behind the plunger, pushes it outward and permits the refilling of the cylinder with oil 95 when the toe is turned away from the plunger in the closing movement of the wings.

The rocker in Fig. 8 is indicated in the position shown in Fig. 1, but is represented merely in dotted lines, as it would not appear in the drawing at the section plane 100 through the check-cylinders.

The wings A and B open normally in opposite directions, but are connected with one another by an automatically detachable coupler so that when the inwardly opening 105 wing is subjected to undue pressure, as in times of fire or panic, it is released from its wing-crank, and swings freely outward so as to open the entire doorway fully.

To permit the wing A to swing in the same direction as the wing B , the wing-crank of the wing A is fitted loosely upon its pivot C and is connected detachably with the pivot by a release-arm t , the hub of which is attached rigidly to the pivot by a pin u' , as shown in Figs. 1, 2, 4 and 5. The wing-crank d , as shown in Fig. 5, has a circular flange t' with a notch v at one end, and the wing-crank d is fitted loosely to the hub u and is coupled normally to the release-arm by a link v^2 having a roller v' at one end arranged to engage the notch v . 110 115 120

A spring w presses the roller v' strongly toward the notch v and operates to hold the wing-crank in normal operative connection with the pivot C until undue force is exerted, pushing the door-wing A contrary to the movement of its wing-crank, and this draws the roller out of the notch v and 125 leaves the wing A entirely free to move 130

outward similarly to the wing B, the roller then bearing upon the flange t' . This gives an unobstructed egress through the whole doorway.

- 5 Any detachable connection between the wing-pivot and its wing-crank would serve the same purpose.

The construction described above shows the combination with the connections between the wing-cranks, of a controller adapted to check the door-wings in their closing movement and to arrest them gradually when fully open; the connections being duplicated where necessary in order to divide the load upon all the connecting parts.

The control-box is also provided with duplicate checking devices, each of which sustains a part of the load and thus avoids overstrain.

It will also be understood from the previous description, that the duplex connections operate the same whether connecting the wings directly or through the mediation of the rocker, and serve as a security against the disabling of the connections, by dividing the strain between the duplicate parts.

The construction, as shown in Fig. 1, furnishes operative connections between the door-wings and the checking-device when the doors are pivoted between two walls, or close to the door-frames.

The compactness of the mechanism permits it to be located above the tops of the door-wings beneath an ordinary transom and the mechanism wholly inclosed in a housing so as not to mar the architectural appearance of the door, while at the same time the sides of the housing may be hinged so as to afford ready access to the mechanism.

The automatic detachment of one of the door-wings from its connection to the other wing affords a free opening through the doorway whenever undue pressure is exerted upon the wing which swings normally inward.

Having thus set forth the nature of the invention what is claimed herein is:

50 1. In a door having wings movable in opposite directions, the combination, with the pivots of the wings, of a rocker journaled intermediate to the said pivots, and duplex connections connecting the pivots to the rocker.

2. In a door having wings movable in opposite directions, the combination, with the pivots of the wings, of a rocker journaled intermediate to the said pivots, duplex connections connecting the pivots to the rocker, and a door-check connected to said rocker to regulate the closing of the door-wings.

3. In a door having wings movable in opposite directions, the combination, with the pivots of the wings, of a rocker journaled

intermediate to the said pivots, duplex connections connecting the pivots to the rocker, a duplex door-check connected to said rocker, and a plunger for arresting the wings gently, when approaching the full open position.

4. In a door having wings movable in opposite directions, the combination, with the pivots of the wings, of two wing-cranks fitted reversely to each of the pivots, and the opposed cranks on the pivots connected by duplex connecting-rods.

5. In a door having wings movable in opposite directions, the combination, with the pivots of the wings, of cranks fitted reversely to the pivots, a rocker journaled intermediate to said pivots, and duplex rods connecting the opposite ends of the rocker to the opposite cranks upon the pivots.

6. In a door having wings movable in opposite directions, the combination, with the pivots of the wings, of wing-cranks fitted reversely to the pivots, the arms of the wing-cranks connected by duplex rods, and springs operating to normally close the door-wings.

7. In a door having wings movable in opposite directions, the combination, with the pivots of the wings, of wing-cranks connected by rods having means for adjusting the length of such rods, for the purposes set forth.

8. In a door having wings movable in opposite directions, to balance gravity, inertia or wind-pressure, the combination, with the pivot of each wing, of a wing-crank operating upon the base of each wing, a connecting-rod jointed to the said wing-cranks and arranged to move the wings reversely, a control-box provided with a checking-device intermediate to the wing-cranks, the control-box having a spindle connected with the checking device, and a rocker-arm upon such spindle jointed to the connection of the wing-cranks.

9. In a door having wings movable in opposite directions, the combination, with the pivots of the wings, of a two-armed wing-crank applied to each pivot, a control-box provided with a checking device intermediate to the wing-cranks, the control-box having a spindle connected with the checking-device, a rocker movable with the said spindle, two rods from each wing-crank connected to adjacent crank-pins upon the rocker, and the rocker serving to operate both arms of each wing-crank and thus have a duplicate connection to both door-wings.

10. In a door having wings movable in opposite directions, the combination, with the pivots of the wings, of a rocker journaled intermediate to the said pivots, duplex connections connecting the pivots to the rocker, a closed casing adjacent to said rocker, the rocker having a spindle with a double-arm check-lever movable in said casing, the cas-

- ing having cylinders substantially in line with the ends of said arms, pistons in the cylinders with links connected reversely to the said lever-arms, and a fluid passageway connecting the cylinders to equalize the pressure therein, and having a screw-valve to regulate the closing speed of the door.
11. In a door having wings movable in opposite directions, the combination, with the pivots of the wings, of a rocker journaled intermediate to the said pivots, duplex connections connecting the pivots to the rocker, a closed casing adjacent to said rocker provided with one or more check-cylinders, a cylinder-socket having a plunger fitted thereto, the rocker having a spindle with a check-lever movable in said casing, a piston in the check-cylinders connected to the check-lever, and the said check-lever being arranged and operated to collide with the said plunger as the door-wings approximate their full opening.
12. In a door having two wings both hinged to move outwardly, the combination, with the pivots of the wings, of wing-cranks applied to the pivots and connected together to move the wings normally in opposite directions, and one of the cranks having a detachable connection with its pivot adapted to yield and release the wing when subjected to undue pressure, thus opening the entire doorway outward when required.
13. In a door having two wings both pivoted to move outwardly, the combination, with the pivots of the wings, of wing-cranks applied to the pivots and connected together to move the wings normally in opposite directions, a release-arm secured rigidly to one of the pivots, the wing-crank upon such pivot being fitted to turn loosely thereon and provided with a notched flange, a link jointed to the release-arm and having a roller adapted to fit the notch in the flange and means for pressing the link to hold the roller elastically in the notch, whereby an undue pressure upon the link pulls the roller out of the notch and releases the wing-crank from the pivot, thus permitting the wing to swing contrary to its normal direction.
14. In a door having wings movable in opposite directions, the combination, with the cranks, of pivots upon their upper ends, a housing-floor sustained upon the door-frame beneath the top of the same, and having bearings for the pivots, wing-cranks applied to the pivots and connected to move the wings in opposite directions, and hinged sides upon the housing between the said floor and the top of the door-frame to inclose the mechanism and give access to the same.
15. In a door having wings movable in opposite directions, the combination, with the pivot of each wing, of a wing-crank applied to the same, a connecting-rod connected to the said wing-cranks to move the wings reversely, such rod having the body formed with screw-thread, and heads screwed adjustably upon the ends of the rod to engage the pins or studs upon the wing-cranks.
16. In a door having wings movable in opposite directions, the combination, with the pivot of each wing, of a two-armed wing-crank applied to each pivot, a control-box provided with a checking-device intermediate to the wing-cranks, the control-box having a spindle connected with the checking-device, a rocker movable with the said spindle, two rods from the arms of each wing-crank connected to adjacent crank-pins upon the rocker, each rod having the body formed with screw-thread and heads screwed adjustably upon the rod and engaged with the pins or studs upon the crank-arms and the rocker, the rods thus permitting the adjustment of the wings with respect to each other and to the center of the doorway, and to cause the operation of the checking device to be effected earlier or later in the movement of the wings as they approach the closing point.
17. In a door having wings movable in opposite directions, the combination, with the pivots of the wings, of a rocker journaled intermediate to the said pivots, connections from the pivots to the rocker to move the wings in opposite directions, a control-box adjacent to the rocker, the rocker having a spindle with a check-lever thereon movable in the said box, a check-cylinder or cylinders substantially in line with the arm of the check-lever and having a port l' at its outer end, and a piston moved in the cylinder by the check-arm to close the said port and having its surface beveled to effect such closing gradually, substantially as herein described.

In testimony whereof I have hereunto set my hand.

THEOPHILUS VAN KANNEL.
